CLAIM

The ornamental design for a combined liquid container and applicator as shown and described.

DESCRIPTION

FIG. 1 is a top left perspective view of a combined liquid container and applicator in an open position in accordance with the claimed design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines consisting of evenly spaced lines in the figures show portions of the combined liquid container and applicator that form no part of the claimed design.
